CABIN FOR SAILBOAT OR THE LIKE

Andrew T. Kostanecki, New Canaan, Conn., assignor to
Bangor Punta Operations, Inc., Greenwich, Conn.

Filed Sept. 8, 1970, Ser. No. 24,863

Term of patent 14 years

Int. Cl. D12—06

U.S. Cl. D71—1

Fig. 2.

FIG. 1.

FIG. 6.

FIG. 1 is a side elevation view of a cabin for sailboat or the like, showing the new design, which has the same appearance as on the other side;

FIG. 2 is a top plan view thereof;

FIG. 3 is a perspective view thereof.

FIG. 4 is a rear elevation view of a modified form of cabin for sailboat or the like wherein the only difference resides in the location of the hatch and companionway being disposed off the centerline of the cabin;

FIG. 5 is a perspective view of the cabin of FIG. 4, with the cabin in a raised position; and

FIG. 6 is a perspective view of the cabin of FIG. 5 wherein the only difference is the addition of a boom tent.

The broken lines showing the mast, sails, and hull of a sailboat are used for illustrative purposes only.

I claim:

The ornamental design for a cabin for sailboat or the like, substantially as shown and described.
